LOCKSTITCH SHOE SOLE SEWING MACHINES
Joseph R. Ioannilli, Beverly, Mass., assignor to United
Shoe Machinery Corporation, Boston, Mass., a corpora-
tion of New Jersey

Filed July 23, 1958, Ser. No. 750,392
35 Claims. (Cl. 112—32)

The present invention relates to lock stitch shoe sole sewing machines and, more particularly, to improvements in the type of sewing machine which is provided with locking loop forming and inserting devices as distinguished from the type having a locking thread carrying shuttle, about which each loop of machine or needle thread is passed in forming a conventional lock stitch seam. In certain of its features, however, the invention is not limited to shoe sewing machines of the loop lock form but is capable of use to advantage with machines for inserting stitches of other forms. In other respects the invention is intended to facilitate and simplify the operation of machines similar to that disclosed in an application for United States Letters Patent Serial No. 543,321, filed October 28, 1955 in my name (now Patent No. 2,877,725, granted March 17, 1959).

In sewing a shoe outsole by machine a problem always has existed at the end of a sewing operation to provide a simple trouble-free method of severing the thread running from the machine to the shoe. The usual practice is to provide means for releasing the tension on the thread in the machine so that the shoe together with a substantial length of thread may be withdrawn until the shoe may be turned to a position where the thread may be trimmed so close to the surface of the shoe sole that its end is inconspicuous. In spite of many attempts to provide automatic devices for severing thread with this type of machine, none has proved satisfactory heretofore for a number of reasons, among which are:

(1) The difficulties of maintaining a keen cutting edge on a thread severing knife;

(2) Preventing displacement of the final stitch in a seam by reason of tension exerted on the thread while being severed by a dull knife;

(3) Providing the proper length of thread for starting a new seam;

(4) Complete severance of the thread to avoid unsightly fringed ends;

(5) Withdrawing a length of thread from the machine before severing so that another trimming operation is required to remove an excessive length extending from the first stitch in a new seam; and

(6) Waste of thread in trimming.

A preferred practice, therefore, still comprises severing thread from a shoe at the end of a seam by employing a hand-held knife and withdrawing only that amount of thread with the shoe at the end of a seam needed for severing closely to the shoe where the thread end will be inconspicuous.

The thread required in sewing shoes either with welts, insoles and uppers for an inseam or with welts and outsoles for an outseam is of such large size that the resistance offered to the passage of a knife edge contributes to the problem of severing the thread, which is generally impregnated with wax or other compound to lubricate its passage through the shoe parts, to seal the interstices between thread fibers against entry of contaminating materials and to seal the perforations formed by the stitches after insertion. For these reasons the difficulties are far greater than are met with light weight sewing machines employing a dry thread of a size which may readily be broken merely by tension exerted on the final stitch of a seam.

2

When utilizing a hand-held knife it is usual in cutting a thread to direct the edge of the knife against a surface of the shoe as a cutting block, so that complete severance is insured and displacement of the last formed stitch in a seam as the result of tension exerted by the knife is avoided. Cutting the thread against the shoe always causes damage to the shoe, so that care must be taken in selecting a surface which will thereafter be covered up by other parts, such as that portion of a bottom surface obscured by a later applied heel.

It is an important object of the present invention to simplify the operation of a shoe sole stitching machine by the provision of automatic means for severing the sewing thread with greater reliability than heretofore, so close to the surface operated upon that in starting a new seam the end of the thread remaining in the machine will be drawn close to or fully into the work to a position where it is inconspicuous, not requiring trimming or further attention on the part of the machine operator. In this connection it is also an object to provide thread severing devices of such nature that there is no danger of exerting an excessive stitch displacing tension on the thread running to the seam, the last formed stitch always being left in the same position at which it was finally set in the substance of the shoe. Further objects of the invention are to provide a work support having an electrically heated thread severing member mounted thereon and an improved form of said thread severing member particularly adapted for use in a wax thread curved needle sewing machine, wherein space limitations are highly restricted and the problem of heat insulation is particularly troublesome.

Other objects of the invention, more particularly relating to a sewing machine having loop lock forming and inserting devices, include improving the arrangement and mode of operation for a needle loop retractor and a locking threaded loop carrying and inserting finger mechanism, so arranged that a more reliable construction than heretofore is obtained with greater durability and ease of operation than in the machine of the prior application. It is also a purpose of the invention to improve the operation of the prior machine by the addition of thread pull-off devices acting in stopping and starting the machine to insure accurate and reliable positioning of the end of the thread remaining in the machine for successfully forming a new stitch in a seam.

It has been found that threads ordinarily employed in sewing machines and particularly those of the shoe sole sewing type are subject to relatively heavy stresses approaching and frequently surpassing their yield points during normal sewing operations. In a shoe sole sewing machine these yield points may reach an intensity of 100 pounds under operating conditions of normal temperature and humidity. To reduce the possibility of yielding beyond their elastic limits and otherwise to improve the seams inserted, it is common to treat sewing threads before use with solutions of waxes, resins, and other fiber modifying materials. Frequently, the characteristics of thread are further improved by a moderate application of heat controlled carefully to avoid any approach to that temperature which will reduce the yield point appreciably. One purpose for the thread treatment is to retain uniformly in the thread a maximum amount of tensile strength consistent with toughness and elastic capabilities. The use of fiber modifying materials and moderate heat, however, increases the difficulties met in the use of a knife edge for severing the thread in a sewing machine.

Instead of depending upon the use of a knife edge to sever the thread in a sewing machine, of the type referred to, the present invention proposes the use of thread severing means arranged to be engaged with the thread

at the end of a seam and heated to a relatively high temperature above that which begins to reduce the tensile strength of the thread to such an extent that it is rendered capable of unlimited yielding action under a relatively light pull exerted against the last formed stitch in the seam without displacing that stitch. For so doing the heat of the severing means acts to evaporate the fiber modifying solutions on the thread and is constructed to be mounted directly on one member of a clamp for the work piece, so close to the work-engaging surface thereof that the thread may be severed with an inconspicuous end remaining on the work piece without heating the work piece to a temperature which will be injurious to the latter. Preferably, a nipper jaw also is mounted on the work clamp in a manner to deflect the thread into engagement with the heated severing member, so as to exert a severing pull on the thread, as well as to hold the severed end remaining in the machine at a position conducive to the proper formation of the first stitch in a new seam. In its illustrated form the severing means comprises an electrical resistance member, the temperature of which is controlled by a heating circuit containing an energizing switch and other essential components.

The needle thread loop retractor, according to a feature of the invention, co-operates with a loop spreader and the needle, each loop of needle thread being withdrawn from the work in the form of an open triangular loop which defines a plane at an angle to the line of the seam being inserted, together with actuating mechanism effective to cause the spreader to enter each loop of thread from that side of the point of operation opposite to the completed stitches of a seam, the retractor both engaging and lifting the thread from the needle hook with a continuous movement.

Instead of employing a locking thread carrying finger, such as disclosed in my prior application, which finger enters each spread loop of needle thread from outside the arc of curvature of the curved needle, it has been found that a marked improvement in operation of the present machine and an improved facility for presenting a shoe is obtained by arranging the mechanism for actuating the present improved locking thread carrying finger in such a way that it enters each needle loop from within the arc of needle curvature. By actuating the locking thread carrying finger from within the arc of needle curvature, greater visibility is afforded about the sewing point for the operator and less opportunity for interference is given between the locking thread finger and the shoe being presented to the machine.

The loop lock stitch sewing machine of the prior application employs means for measuring a predetermined length of thread for each stitch and at least one thread lock co-operating with the measuring means is provided against which thread lock each stitch is set in the work. In order to facilitate the insertion of the first stitch in a new seam, particularly in machines employing a thread cutter, an essential degree of accuracy required in starting a new seam without trimming thread extending from the first stitch is obtained in the illustrated machine by providing a pull-off located along the length of thread running from the thread lock to the thread supply. The pull-off with this feature of the invention is actuated at the end of a seam while the thread lock remains closed, so that there is no possibility for the take-up to withdraw the thread end from its proper position in forming and setting the first stitch of a new seam. Thus, the thread lock serves two purposes; one to assist the measuring means in withdrawing thread in the proper predetermined length from the supply for completion of each stitch in a seam and the other to prevent displacement of the thread end during operation of the pull-off at the end of the seam. Where, as in the present instance, a driving and stopping mechanism controls the operation of the machine, the proper operation of the pull-off is

accomplished by connecting it to the driving and stopping mechanism.

Other features of the invention consist in the devices, combinations and arrangements of parts as hereinafter described and claimed, the advantages of which will readily be understood from the accompanying drawings, in which:

FIG. 1 is a view in front elevation of the left hand portion of a shoe outsole stitching machine, including features of the present invention, parts of the machine having been broken away and reduced in height to enable the use of a larger scale in the remaining parts of the illustration.

FIG. 2 is an enlarged view of a portion of the machine shown in FIG. 1;

FIG. 3 is a sectional view on an enlarged scale, looking along the line III—III of FIG. 2 and showing the position of a shoe at the end of a seam in the machine of that figure;

FIG. 4 is a view in rear elevation and on a slightly reduced scale of a portion of the driving and stopping mechanism in the machine;

FIG. 5 is a similar view on a larger scale of a portion of the mechanism shown in FIG. 4 but with additional parts broken away to illustrate more clearly the underlying parts of FIG. 4;

FIG. 6 is a detail view in right side elevation of a treadle connected part in the driving and stopping mechanism of FIG. 5;

FIG. 7 is a plan view of a portion of the same mechanism showing a locking thread pull-off with the parts illustrated in positions assumed while the machine is at rest;

FIG. 8 is a similar view of the parts of the locking thread pull-off in positions assumed while sewing operations are continuing;

FIG. 9 is a sectional detail view in rear elevation on a somewhat enlarged scale taken along the line IX—IX of FIG. 8;

FIG. 10 is a sectional detail view on a somewhat smaller scale, looking from the right side of the machine and illustrating the positions of the parts just before the machine comes to rest at the end of a seam;

FIG. 11 is a similar view of some of the parts in front of those shown in FIG. 10, illustrating their positions during sewing operations;

FIG. 12 is an enlarged front view of portions of the machine surrounding the point of sewing operations, illustrating a locking thread severing member;

FIG. 13 is a detail view in right side elevation showing the operations of the locking thread severing member on a shoe illustrated in section;

FIG. 14 is a view in left side elevation of the locking thread severing member in a modified form having a thread directing guard to insure proper engagement of the thread therewith;

FIG. 15 is a detail view in front elevation of the locking thread severing member;

FIG. 16 is a sectional detail view in left side elevation illustrating a thread measuring action performed by the locking thread measuring member;

FIG. 17 is a sectional detail view on a further enlarged scale of a locking thread friction device as viewed in the direction of the arrow XVII in FIG. 16;

FIG. 18 is a detail plan view of a needle thread severing member mounted on the work support of the machine, together with a thread end clamping device;

FIG. 19 is a sectional detail view in front elevation of the parts in the machine surrounding the sewing point and including the thread end clamping device;

FIG. 20 is a sectional detail view in front elevation and on a slightly enlarged scale, looking along the line XX—XX of FIG. 18, and showing the construction of a work support having the needle thread severing device mounted thereon;

FIG. 21 is a sectional detail view taken along the line XXI—XXI of FIG. 18 and on the same scale as FIG. 20, illustrating more clearly the relationship with the work support of the thread severing member and a portion of the shoe during sewing operations;

FIG. 22 is a sectional detail view in right side elevation of the same parts shown in FIG. 21, taken after the needle thread has been severed;

FIG. 23 is a detail view looking from above the thread severing member;

FIG. 24 is a detail view looking from the front of the thread severing member;

FIG. 25 is a sectional detail view in left side elevation, illustrating the construction and operation of the needle thread severing member and a needle thread retractor;

FIG. 26 is a similar detail view in left side elevation of the needle, loop spreader, thread severing plate and needle thread end nipper jaw, showing the manner in which the thread end is pulled into the work during formation of the first stitch in a seam;

FIG. 27 is a detail perspective view looking from the left front, showing portions of the thread-engaging devices surrounding the sewing point in the machine, taken with the locking thread carrying finger retracted after the first stitch in a seam is formed and is about to be set in the work;

FIG. 28 is a similar view of the same parts showing the position of the locking thread carrying finger after entry within a spread needle loop with the needle thread retractor before disengaging the thread from the needle;

FIG. 29 is a plan view of the parts shown in FIG. 28 in the same positions as in that figure;

FIG. 30 is a sectional detail perspective view showing close cut, inconspicuous thread ends at the starting end of a seam as inserted in a shoe by the present machine;

FIG. 31 is a similar view illustrating the positions of close cut thread ends at the completion of a seam as inserted by the machine;

FIG. 32 is a plan view of a wax pot in the machine and a needle thread pull-off co-operating with the thread running therefrom;

FIG. 33 is a detail view in left side elevation of mechanism for actuating the needle thread pull-off, including connections with a driving and stopping mechanism for the machine;

FIG. 34 is an enlarged detail view in right side elevation and partly in section showing the action of the pull-off on the thread;

FIG. 35 is a detail perspective view of the needle and locking thread supply and control system, including measuring and pull-off devices as they appear from the left front of the machine, including a portion of a shoe sole being sewn;

FIG. 36 is a schematic wiring diagram of the electrical circuits in the machine;

FIG. 37 is a fragmentary plan view of a modified form of work support and a needle thread severing member mounted thereon;

FIG. 38 is a similar view of the modified work support with the thread severing member removed;

FIG. 39 is a perspective detail view of a guard strip for the thread severing member;

FIG. 40 is a sectional detail view of a portion of the modified work support looking from the right side;

FIG. 41 is a sectional view of the modified work support taken along the line XLI—XLI of FIG. 38;

FIG. 42 is a similar sectional view taken along the line XLII—XLII of FIG. 38;

FIG. 43 is a sectional view of the modified work support taken along the line XLIII—XLIII of FIG. 37;

FIG. 44 is a perspective detail view of an alternate form of thread severing member; and

FIG. 45 is a sectional view of the modified work support corresponding to that shown in FIG. 42 with the

alternate thread severing member and the guard strip in place.

The illustrated machine is similar in many respects to that disclosed in the application above referred to and

5 is equipped with a curved hook needle 2 (see FIG. 27), a curved awl 4, a loop lifter and spreader 6 at the side of the work with the needle, a needle looper 8, a thread finger 10 (FIG. 2), a work feeding clamp comprising a work support 12 toward which the needle operates in 10 penetrating a work piece and against which the work piece is pressed by the thrust of the needle, and a presser foot 14 acting at the side of the work piece from which the thrust of the needle is exerted to clamp the work piece against the work support.

15 To control the movements of the thread a stitch setting take-up 16 (FIGS. 1 and 35) is mounted below the work support and there are provided front and rear thread locks 18 and 19, and guiding trucks 20 of a needle thread measuring mechanism separate from the needle, including

20 a thread measuring arm 22, the position of which is automatically adjusted by the position of the presser foot while engaging the work. The take-up 16 acts in the usual way to draw each needle loop into the work with a surrounded loop of locking thread and to set the

25 stitches thus formed. Co-operating with the measuring arm is a pull-off comprising an arm 24 oscillating between guide eyes in the arm 22 to measure more or less thread as the work engaged by the presser foot varies in thickness or when work pieces of different thicknesses 30 are operated upon. When the take-up sets each stitch the rear thread lock 19 grips the thread to insure uniform tightening of the stitch.

The illustrated machine is also provided with mechanisms for actuating the stitch forming devices in proper

35 timed relationship to interlock each loop of thread retracted from the work piece by the needle with a loop of locking thread, which loop of locking thread is introduced into each loop of needle thread to lock the needle thread loop against retraction. For this purpose a locking

40 thread carrying finger 26 (FIG. 27 et. seq.) is mounted at the side of the work with the needle, a locking loop detaining finger 28 acting to prevent withdrawal of the locking loop from the needle thread as the locking thread carrying finger is withdrawn.

45 As in the machine of my prior application the formation of each stitch is started by the penetrating stroke of the awl 4 through a work piece, such as a welt 30 and an outsole 32 of a Goodyear welt shoe, as illustrated in FIGS. 3 and 13. The shoe is manually presented to

50 the machine while mounted upon a last 34 and comprises an insole 36 and an upper 38 attached to a rib on the insole and to the welt by an inseam 40. After the awl has formed a perforation in the outsole and the welt, the needle follows the awl into the work piece as the awl withdraws. Thereafter, the looper 8 lays a portion of the

55 needle thread 42 in the hook of the needle and the needle withdraws through the work piece to a fixed position with a loop of needle thread, the thread finger providing sufficient thread between the previously formed stitch and the

60 stitch being formed, to avoid the necessity of any slippage in the hook of the needle as the needle withdraws. By the time the needle disengages the work the thread finger has released the thread and the needle approaches its uniform position of maximum withdrawal from the work piece.

65 The loop spreader 6 then moves forwardly into the path of the needle, separating one side of the needle loop from the other into a uniform triangular shape, the plane of which is disposed at right angles to the line of the seam inserted, as shown in FIGS. 28 and 29 to admit the locking thread carrying finger 26. As soon as the locking thread carrying finger has entered the spread loop of needle thread 42, as shown in FIG. 28, the thread detaining finger 28 moves into a loop of locking thread 44 and strikes the upper surface of the outsole 32, forming an indentation 46 (see FIG. 30), to prevent escape of the

locking thread loop when the thread carrying finger is withdrawn from the needle loop. As each stitch is set the thread connecting the needle perforations covers the indentation. In other respects the present machine generally is similar in its mode of operation and construction to that of the prior application.

The illustrated machine, being intended for use in sewing a shoe which is presented to the machine by hand, has a driving and stopping mechanism controlled by the operator for starting the sewing operations and then for bringing the machine to rest at a predetermined position regardless of sewing speed, both the needle and awl being disengaged from the work piece, so that the work piece may readily be withdrawn from the machine. The driving and stopping mechanism is provided with a main driving clutch having a driving pulley 48 (FIG. 1), which is brought into engagement with a clutch facing on a hand wheel 50 secured to a main sewing shaft 52 (see FIGS. 1, 3, 10, and 12). The sewing shaft 52 is geared to rotate with a second shaft 54 (FIG. 3), both of which shafts have secured to them a number of cams and cranks for actuating the stitch-forming and work-engaging devices in timed relationship to each other.

To actuate the main driving clutch, the driving pulley 48 (FIG. 1) is shifted by a clutch lever 56 fulcrumed on a stud 58 secured to a frame 60 of the machine and one arm of the clutch lever is operatively connected to a rod 62 pivoted at its lower end to a foot actuated control treadle 64 fulcrumed at 66 on the lower end of the machine frame 60 at a convenient location for foot operation.

To bring the machine to rest at the end of a seam the upper end of the treadle rod 62 also is operatively connected to a cam arm 68 (FIGS. 4, 5, and 6) in a manner to be later described, the free rearward end of which, when the treadle is depressed and the machine is operating, engages a roll 70 on an upwardly extending arm of a lever 72. The lever 72 is in turn connected to control a low speed driving clutch, which when the treadle 64 is released by the operator, is thrown into operation, first to retard rotation of the sewing shafts and then automatically to be rendered inoperative when the sewing shafts reach predetermined angular positions, in which the needle and awl are disengaged from the work. To bring the machine to rest with further accuracy the main sewing shaft 52 has keyed to it a cam 74 (see FIG. 10) arranged to be actuated by a pawl lever 76 moved outwardly away from the shaft 52 for performing certain auxiliary operations, such as raising the presser foot from the work piece at the end of a seam. The cam 74 also has a radial shoulder acting positively to limit rotation of the sewing shaft, if necessary, in case momentum of the parts has not been reduced sufficiently by the low-speed driving clutch and the frictional forces in the machine.

The connections actuated by the pawl lever 76 for performing the auxiliary operations include an arm 78 connected by a link 80. The arm 78 supports the pawl lever 76 for movement axially of the shaft 52 into and out of alinement with the cam 74 and the link 80 is pivotally connected to a lever 82 rotatable on a stud 84 secured in the machine frame 60. For raising the presser foot from engagement with the work piece, the upper end of the lever 82 is forced rearwardly against a vertical arm 86 (FIGS. 4 and 10) secured to a rock-shaft 88 rotatable in the machine frame. Also secured to one end of the shaft 88 is a rearwardly extending arm 90 (FIG. 4) pivotally connected to a downwardly extending link 92, having a connection with the presser foot 14. During the final angular movement of the sewing shaft 52 the cam 74 presses the pawl lever 76 rearwardly, releasing the work piece from clamping engagement by the presser foot. The construction and operation of the driving and stopping mechanism, thus briefly pointed out, is generally similar to that disclosed

in United States Letters Patent No. 2,271,611 granted February 3, 1942, and No. 2,316,761, granted April 20, 1943, both in the names of Fred Ashworth et al. Further reference will be made to these patents hereinafter.

The machine of inventor's prior application above identified, is equipped with connections between the driving and stopping mechanism for opening a pair of thread locks similar to those indicated at 18 and 19 (FIG. 35) in the machine of the present invention, as the machine is being brought to rest at the end of a seam, in order that a work piece may readily be removed from operating position in the machine with both the needle and locking threads extending from the final stitch without displacing the final stitch or otherwise retarding the removal of the work piece. After withdrawing the work piece with the threads still attached the operator is able to apply the cutting edge of a hand-held knife to the threads close to the work, thus severing them from those portions extending from the machine. Two severing operations ordinarily are required at the end of a lock stitch outseam, since two threads from the final stitch extend, one downwardly and the other upwardly from the work piece. Under some circumstances both threads may be severed at the upper surface of the work piece if both are exposed thereon. However, such exposure is not always convenient and normally two severing operations are required, one for the locking thread and the other for the needle thread. Besides necessitating special care on the part of the operator in severing threads, lengths of thread usually are withdrawn from the machine with the work piece, so that in starting a new seam these withdrawn lengths must be trimmed close to the work piece as a supplemental operation. Besides wasting thread in such trimming operations, the factory floor surrounding a shoe sewing machine is commonly covered with sticky wax thread ends, which adhere to the feet of the factory workers and clog supporting wheels of racks employed for transferring shoes from one machine to another.

To avoid the difficulties encountered in trimming the threads connected to the ends of a seam in a shoe or similar article and to eliminate the necessity for a sewing machine operator to hold in his hand a keen edged thread severing knife at all times, the machine of the present invention is provided with automatic thread severing means mounted so close to the surface of the work piece, while in its clamped position between the work support and the presser foot, that no further trimming of the thread is required after removal of the shoe from the machine, the thread being severed by an effortless pull exerted against the the last formed stitch without any danger of displacing or otherwise disturbing the last formed stitch in the work piece. For these purposes the thread lock 19 is retained in closed thread gripping position and the pull on the thread is exerted against it. The severing means is in the form of an electrical resistance member heated above a temperature at which the thread displays any appreciable tensile strength, regardless of whether the thread is composed of natural or synthetic fibers. Thus, the thread in its heated condition is capable of unlimited yielding action and ultimate separation at the heated point. With the use of synthetic fibers the temperature ordinarily employed is less than that required with natural fibers but, in any event, the quantity of heat developed to maintain this temperature must be kept somewhat below that which will induce self-sustaining combustion or damage to a work piece or surrounding materials, in spite of the closely spaced relationship with the heated member.

The temperature of the thread severing member is carefully regulated during the major portion of each seam to keep the temperature below that which will cause flash burning or excessive heating of the parts of the machine surrounding the operating point. To these ends the physical dimensions of the heated member are reduced to their

smallest possible size and the over-all average amount of heat developed is kept as low as possible by special expedients. Thus, with natural fiber threads requiring temperatures higher than synthetic fiber threads, it is highly desirable to lower as much as possible the intensity of heat applied to the severing member or at least to reduce the quantity by discontinuing its application while the machine is at rest and also while the machine is operating, the heat being applied only momentarily after the end of the sewing operation is reached. With these restrictions it has been found that the possibility of heat damage to leather in shoes, or to work pieces of other materials is negligible and that the hazard of igniting uncontrollable combustion is avoided even under the worst conditions of poor safety standards found in nonfireresistant building construction common to shoe factories.

The heated thread severing member of the present invention consists of an integral U-shaped plate 94, best shown in FIGS. 23 and 24. One arm of the U-shaped plate is in the form of a perforated lug 96 for convenience in electrical connection and mechanical securement to the work support 12, and the work support has a threaded opening to receive a clamp screw 97 passing through the lug (FIG. 21). The other arm of the severing plate is in the form of a soldering lug 98 for convenient electrical connection to heating circuits, to be described more fully hereinafter. The severing member has a base 100 wherein the heat, produced by passage of electrical current, is concentrated through the use of a cross-sectional area in the base smaller than that in the arms 96 and 98. For the purposes of the present invention it has been found that the length of the base 100 on the severing plate may be reduced to less than one quarter of an inch and the voltage applied to the arms of the plate may be as low as two volts, the current flow being in the neighborhood of 40 amperes.

To insulate and otherwise to prevent short circuits between the soldering lug 98 and the work support 12, which is normally constructed of steel, the base 100 is formed with a spacing channel 102 along its under surface and the soldering lug 98 has a refractory porcelain coating 104 (FIG. 24) along its under surface.

To accommodate the thread severing plate 94 with the greatest possible protection for the work, the thread, and the adjacent parts of the machine from damage by heat radiation and conduction, the work support 12 is shaped to enclose the heated portion of the plate except along the extreme forward edge of its base 100 (see FIGS. 20, 21, and 22).

The work support 12 is similar to that of the machine in Patent No. 2,271,611, above referred to, and is provided with a shoe or other work-engaging surface 106 intersected by an opening 108 to admit passage of the needle and awl. Entering the needle and awl receiving opening 108 from the rear side is a slot 110 of somewhat larger dimensions than those of the thread severing plate 94. When the base 100 of the thread severing plate is inserted within the slot 110 its extreme forward edge is brought into line with the rear wall of the needle opening 108, the rear wall of the needle opening thus serving as a guard to prevent accidental contact of the sewing thread with the plate 94 during sewing. The dimensions of the slot 110 are greater than those of the plate 94 to afford a heat insulating space between the severing plate and the work support.

To bring the needle thread 42 into engagement with the heated thread severing plate 94 and to apply a severing pull to the thread while engaged with the plate, the illustrated machine is provided with a thread nipper jaw 112 (see FIGS. 18 to 22) rotatably mounted for swinging movement toward and from the path taken by the thread 42 through the needle opening 108 of the work support, as shown in FIG. 21. The nipper jaw 112 is in the form of relatively thin strap material bent into a configuration to lie close along an upper surface of the work support

with its thread engaging end disposed to slide beneath an apron 114 (FIGS. 19 and 20) formed integrally with the work support at the left side of the needle opening 108. Beneath the apron 114 the work support is provided with a grooved shoulder 115 against which the thread is gripped after being deflected by the nipper jaw. The nipper jaw is similarly grooved and formed with ridges co-operating with the grooves on the shoulder 115.

The shoulder 115 is located along the path taken by the needle thread between the heated plate 94 and those stitch-forming devices disposed below the work-engaging surface 106, so that when the thread is severed the end remaining in the machine will be gripped closely at a position where the thread may effectively be manipulated by the stitch-forming devices in starting a new seam to insure formation of the first stitch in a new seam with a short inconspicuous thread end (FIG. 30). The nipper jaw thus tensions the thread by deflecting it from its normal straight line position of FIG. 21 extending between a work piece and the looper 8, by engaging the thread with the heated thread severing plate and by gripping the thread with a single instantaneous movement.

As soon as the thread is severed by the heated plate 94, the shoe may be lifted freely from the work support without withdrawing the needle thread from the grip of the nipper jaw (see FIG. 14). Accordingly, there is no necessity for releasing the tension on the needle thread by opening either of the thread locks 18 or 19 or otherwise reducing the thread tension. The only remaining impediment acting to resist removal of the shoe, therefore, is the connection of the shoe with the locking thread 44.

To sever the locking thread from a shoe at a location close to the tread surface of the outsole 30, thus insuring a neatly finished appearance at the end of a seam, a second heated member in the form of an electrically conductive U-shaped plate 116 (see FIGS. 14 and 15) similar to the needle thread severing plate 94 is mounted at the lower end of a rigid angular strap 118 secured at its upper end to an arm 120 movable with the presser foot 14. The position of the heated plate 116 is such that when the shoe in the solid line position of FIG. 3 is disengaged from the work support 12, it may be engaged by the locking thread 44 in the broken line position of FIG. 3 and the solid line position of FIGS. 13 and 14 close to the point where the thread enters the shoe. Continued movement of the shoe away from the work support to the position of FIG. 16 applies sufficient tension to the locking thread to sever it completely under the action of the heat produced by the heated member 116 without pulling or otherwise disturbing the set position of the threads in the last formed stitch.

To guard the shoe from slight discoloration as the result of accidental contact with the heated plate 116, a curved, notched deflector 122 is secured to the strap 118 just above and in front of the plate 116. One arm of the fork on the deflector is extended into contact with the upper surface of the presser foot 14, the fork straddling the lower heated edge of the plate 116 so that the locking thread is freely engageable therewith.

To enable convenient temperature control of the thread severing plates 94 and 116 electrical heating circuits therefore include adjustable resistors, switches, relays for reducing or cutting off the flow of current through the plate, except when needed, and timing devices for insuring proper heating of the plates 94 and 116 during thread severing operations. Among the advantages obtained by using such components are, complete severance while heating the thread to that temperature only at which the thread fibers yield under a pull less than will displace the last-formed stitch in a seam, formation of tightly curled or congealed fibers at the end of the thread extending from the work piece in such a way that an enlargement is formed to prevent displacement of the thread ends, reduction of electrical power consumption, and all tendency to overheat the machine or the work.

It is seldom necessary in the illustrated machine when operating at the usual sewing speeds to grip the end of the locking thread 44 remaining in the machine after severing it from a shoe, since it quickly swings downwardly from the more nearly horizontal dotted line position of FIG. 16 to the solid vertical position after being severed, where it is readily trapped within the first loop of needle thread withdrawn from the work at the start of a new seam (see FIG. 27). However, to insure proper formation of the first stitch of a new seam the length of the strap 118 and the position of the plate 116 thereon are so chosen that the distance between the heated edge of the plate 116 and the locking thread carrying finger 26 is equal to the length of thread required by the first stitch, indicated at 124 in FIG. 30, as that stitch is set in the work, the end of the locking thread projecting from the tread surface of the sole being drawn close to the sole where it is inconspicuous and unobjectionable.

The locking thread severing plate 116 (FIG. 15) being of the same general configuration as that of the needle thread severing plate 94 is provided with a perforated arm 126 for receiving a mounting screw 128 threaded into the strap 118 and a heating circuit connecting arm 130 between which is a heated base 132. The circuit connecting the arm 130 of the plate is insulated from the strap 118 in a manner similar to that for the needle thread severing plate 94 with a layer of refractory porcelain attached to the end surface of the arm 130 or by means of a rectangular plate of fiber glass insulation 134. Exposure of the edge of the heated base 132 to the locking thread 44 is afforded by forming a recess 136 at the lower end of the strap 118, projections 138 being formed on the strap at either side of the recess.

Because limited lengths of thread ends are left extending from a shoe at the beginning of a new seam, it is necessary to provide thread measuring pull-offs actuated in stopping the machine at the end of a seam, for withdrawing additional lengths of thread from the respective needle and locking thread supplies sufficient in lengths to form the first stitch in a new seam. The lengths pulled off from the respective needle and locking thread supplies must not exceed the requirements for forming a stitch or be withdrawn from the machine before a new seam is started. If they are allowed to be withdrawn from the machine before a new seam is started the amounts withdrawn will project from the first stitch and require trimming. Accordingly, both pull-offs are held in pulling-off position until the work piece is presented to the machine and is clamped in operating position between the work support and presser foot, the amounts pulled off being slightly less than required for actual stitch formation to offset the inherent elastic stretch imparted to the thread by the stitch-forming devices.

The needle thread pull-off is located to act along the length of thread 42 (see FIG. 35) running from the thread locks 18 and 19 to the needle thread supply, indicated at 140, similar to that disclosed in United States Letters Patent No. 1,909,157, granted May 16, 1933, upon application of E. E. Winkley. This thread supply is provided with a resiliently actuated loop of wire 142 which applies a constant light tension to the needle thread. The thread running from the wire 142 passes over pulleys 144 into a wax pot 146. From the wax pot 146 the thread runs through a stripper 148, which in turn adds to the tension on the thread. Just above the wax pot 146 the needle thread is engaged by the pull-off so that the proper length is drawn through the stripper 148 against the light tension of the wire 142, the friction of the stripper ordinarily preventing return movement of the thread by the resilient action of the wire 142.

The needle thread measuring pull-off is in the form of a sliding bar 150, best shown in FIGS. 32 and 33. The sliding pull-off bar 150 has a concave forward end acting on the needle thread 42 as it emerges from the stripper 148. To assist in uniform action of the pull-

off bar 150 the needle thread is pressed against an adjustable measuring arm 152 clamped to a wax pot support bracket 154 by a bolt 156.

The needle thread measuring pull-off bar 150 is formed with a slot 158 near its forward end and another slot 160 spaced rearwardly. Entering these slots are two shoulder screws 162 and 164 threaded at their lower ends in a block 166, forming a part of the machine frame. The bar rests along its rearward portion on the block 166 extending from the frame and the block carries a clip 168 secured thereto by a screw 170, the clip having an angularly bent flange overlying the edge of the pull-off block 166.

In its measuring movement the needle thread pull-off bar 150 deflects the thread 42 from a straight line path between the stripper 148 and a pulley for guiding the thread to the measuring arm 152, the position of the pull-off bar being so adjusted that the proper amount of thread is withdrawn from the supply 140 through the wax pot to insure proper formation of the first stitch of a new seam. To actuate the pull-off bar 150, it has threaded into its rearward portion a clamp screw 172 passing through a slot in a plate 174 secured to the bar. Above the head of the screw 172 is a vertically swinging and horizontally movable finger 176 having a shoulder 178 arranged to be engaged with the rearward end of the plate 174. The finger 176 is pivotally mounted by a shoulder screw 180 on the lower end of a vertical rod 182 fastened by screws 184 to a lower arm of the lever 82 in the driving and stopping mechanism (see FIGS. 4, 10, and 32). At the end of a seam just before the clamping force of the presser foot releases the work piece the finger 176 is actuated against the plate 174 by the lever 82, causing the pull-off bar 150 to move forwardly against the thread. To limit the movement of the pull-off bar the clip 168 has an upstanding projection 186 arranged to engage a cam surface of the forward end of the finger 176. As the finger is moved forwardly from the solid line position of FIG. 34 to the dotted line position, it is raised by the projection 186 to a position disengaged from the plate 174. When the plate 174 is disengaged from the finger 176 the pull-off bar is drawn rearwardly to its initial position by a tension spring 188 stretched between a pin 190 on the block 166 and an angle piece 192 secured to the bar 150.

The timing and adjustment of the needle thread pull-off mechanism and its connection, above described, with the driving and stopping mechanism is such that thread is pulled off the supply reel 140 at the same time the final stitch in a seam is being tightened and set within the work by the take-up 16. At this time the thread lock 19 also clamps the thread against movement to insure proper setting of the stitch and to prevent movement of the thread from the seam in a shoe, the thread being drawn entirely from the supply reel. After the needle thread is pulled off by movement of the bar 150 the presser foot is disengaged from the work and the thread lock 19 is actuated to release the thread surrounding the pulley 20 co-operating therewith.

As a further means to prevent disturbing the clamped position of the needle thread end engaged by the nipper jaw 112, the thread passes from the take-up 16 to the nipper jaw through a frictional tension device comprising a pair of perforated rectangular plates 194 between which the thread passes (see FIGS. 2 and 35). The plates are yieldingly drawn together by a threaded stud 196 secured to the right-hand plate, passing through the left-hand one and through a fixed part on the machine frame 60, the stud being surrounded by a compression spring 198 compressed between the frame and suitable check nuts 200 on the stud. The tension plates 194 also assist in the formation of the stitches by preventing excess movement of the needle thread from the take-up through the work.

The locking thread measuring pull-off member is located to act along the length of locking thread 44 (FIG. 35)

running from a wax pot 202 having a stripper 204 through which the thread passes and a guiding pulley 206. The guiding pulley 206 is located directly above an eye in a fixed guide plate 208, below which the locking thread pull-off in the form of a laterally extending arm of a lever 210 swings. The laterally extending arm of the lever 210 has a thread guide eye at its free end and below the lever the thread passes through corresponding eyes in the ends of a U-shaped bar 212 fixed to the machine frame (see FIGS. 1, 2, 7, 8 and 35). When the eye in the lever 210 moves out of alignment with the eyes in the plate and bar from the position of FIG. 8 (also dotted line position of FIG. 7) to the solid line position of FIG. 7, thread is deflected and withdrawn from the locking thread supply, indicated at 214 in FIG. 35. The locking thread supply is similar to that in the Winkley patent and has a resiliently actuated wire loop 216 which applies a constant light tension to the locking thread. From the wire 216 the locking thread passes through a tension device comprising an angle plate 218 secured to the machine frame and a rectangular plate 220 pressed yieldingly against the plate 218 by a stud 222 passing through openings in the plate 220, the angle plate, a spring 224 and a check nut 226 at the left end of the stud 222. From the tension device 218, 220, the locking thread enters the wax pot 202, so that when the pull-off lever 210 is actuated to the solid line position of FIG. 7 thread is withdrawn from the locking thread supply 214 against the tension exerted by the wire 216, the tension device 218, 220 and the stripper 204 on the wax pot 202. The action of the pull-off 210 occurs before the shoe is released from the grip of the presser foot and work support, at a time when displacement of the locking thread in the work is resisted by confinement within a loop of the needle thread 42 as the last formed stitch in the seam is being set. The pull-off lever 210 then remains in the solid line position of FIG. 7 to hold aside the pulled off length of locking thread until a new seam is started.

To prevent movement of the locking thread 44 through the thread carrying finger 26 in a direction to shorten the free length extending from the thread carrying finger after the threads have been severed additional friction is exerted on the locking thread just before it reaches the thread guiding portion of the thread carrying finger. For this purpose there is secured to the shank of the locking thread carrying finger a torsion spring 228 (see FIGS. 16 and 17) having upwardly and laterally bent arms, one of which is in the form of an eye to receive a clamping screw 230 threaded into the shank of the locking thread finger. The other, laterally bent arm of the torsion spring 228 presses against the rearward surface of the locking thread finger shank and exerts a pressure against the thread 44 passing between the shank and the arm of the torsion spring 228.

The locking thread measuring pull-off lever 210 is fulcrumed on a vertical screw 232 (see FIGS. 7, 8, and 9) passing loosely through a detent arm 234 and the pull-off lever 210 into threaded engagement with the upper end of a bracket 236 secured to the frame of the machine. The pull-off lever 210 is actuated from the dotted position of FIG. 7 in pulling off thread to its solid line position where it is latched against return movement. After the machine is stopped the shoe or other work piece having been removed from operating position and the machine restarted, the pull-off lever is unlatched and returned to its sewing position, shown in FIG. 8 by a tension spring 238 stretched between a pin 240 fixed in the machine frame and a pin 242 projecting from an actuating link 244 (FIG. 8) pivotally connected with provision for adjustment to a rearwardly extending arm of the locking thread pull-off lever.

For actuating the needle thread nipper jaw 112 to deflect the needle thread, to bring it into engagement with the heated needle thread severing plate 94 and to

grip the thread against the shoulder 115 on the work support, the jaw is pivotally mounted at 113 on the work support (FIGS. 18, 19 and 20) and a downwardly extending arm of the nipper jaw is formed with a perforated boss pivotally connected by a pin 246 passing through the forked ends of an actuating link 248 (see also FIG. 2). The opposite end of the link 248 is pivotally connected by a pin 250 with an armature 252 slidably mounted in a solenoid core 254. The solenoid core 254 surrounds a coil 256 (see FIGS. 1 and 2) for an electromagnet, the circuit of which is controlled in a manner, hereinafter more fully described, to actuate the nipper jaw 112 at the proper times.

The locking thread pull-off lever 210 is also actuated by an electromagnet having a coil 258 (FIGS. 2, 3, 7, 8 and 9) surrounded by a core 260 and an armature 262 slidably mounted in the core and pivotally connected by a screw 264 with the actuating link 244. The core 260 is carried by an angle plate 265 secured to the machine frame. To connect the other end of the link 244 with the locking thread pull-off lever 210 for easy adjustment the link has passing loosely through it a shouldered screw 266, the shoulder of which engages a clamp (not shown) acting on the rearwardly extending arm of the pull-off lever which is slotted to guide and be clamped adjustably by the screw 266 in any of a number of positions. By releasing the screw 266 for movement along the slot of the arm the pull-off movement of the lever 210 may be varied to pull off the proper amount of thread required in starting a new seam according to the thickness of the work.

To latch the locking thread pull-off arm 210 in actuated position, shown in the solid line position of FIG. 7, an enlargement of the armature 262 is engaged by a step in a latch block 268 adjustably mounted for lengthwise sliding movement with a tongue and groove connection to the detent arm 234. To secure the latch block 268 against sliding movement on the arm 234, a slot 270 (FIG. 8) in the arm 234 has passing through it a clamp screw 272 threaded into the latch block 268. By adjusting the latch block the latched position of the locking thread pull-off lever, while the machine is stopped may be changed to meet the requirements. To hold the latch block in engagement with the armature the detent arm 234 is acted upon by one end of a spring 274, the other end of which is secured in a rearwardly extending arm 276 of the bracket 236 (see FIG. 3).

To release the locking thread pull-off arm of lever 210 from its latched position, so that the spring 238 may return the lever to its normal sewing position after the machine is started in operation, the arm 234 has a right-angle flange provided with a threaded opening engaged by the threaded end of a disk-headed bolt 278 (FIG. 9) locked in suitably adjusted position in the flange by a check nut 280. Whenever the machine is started in operation the head of the bolt 278 is engaged by the forward end of a Bowden wire 282 passing through a sheath 284 (see also FIG. 7). The forward end of the sheath is made fast to the frame of the machine by a clamp 286 (see FIG. 9) on the bracket 236. The rearward end of the sheath is secured in a clamp brace 288 made fast to the machine frame by screws 290 (see FIGS. 3 and 11). The rearward end of the Bowden wire 282 is connected to a clevis 292 straddling the upper end of an arm 293 secured to the shaft 88, to which arm the clevis is pivotally connected by a pin 294. The adjustment of the bolt 278 and the positions of the ends of the sheath 284 in their clamps are such that at the beginning of a seam as the machine is being started by the driving and stopping mechanism the presser foot is brought into clamping engagement with a shoe and the arm 293 and the Bowden wire 282 are moved forwardly to release the armature 262 from the latch block 268, causing the locking thread pull-off lever 210 to return to its sewing position of FIG. 8 where the thread

pulled off is made available for use by the stitch-forming devices in forming the first stitch of a seam with close inconspicuous thread ends as in FIG. 30.

To energize the circuits for heating the thread severing plates 94 and 116 the upper end of the treadle rod 62 is pivotally connected by a pin 296 to a lever 298 fulcrumed on a bracket 300 secured to the frame of the machine (see FIGS. 1 and 4). The lever 298 is also pivotally connected to the lower end of a rod 302 carrying collars 304 and 306 clamped thereto and engaging between them an arm of the clutch lever 56. The upper end of the rod 302 is pivotally connected to the cam arm 68. For bringing the machine to rest at the end of a seam when the treadle 64 is released the rearward end of the lever 298 supports a pair of adjusting screws 308 operatively connected with a pair of spring pressed buttons 310 and 311 in two double-pole, double-throw energizing switches 312 and 313. When the treadle is released in stopping the machine the adjusting screws 308 are disengaged from the buttons 310 and 311 and the circuits are closed for heating both thread severing plates 94 and 116. Conversely the heating circuits are opened whenever the treadle is depressed to start the machine.

To energize the circuit for actuating the locking thread pull-off lever 210 at the proper time in the last sewing cycle of the machine at the end of a seam, the arm 293 is arranged to engage a button 314 (see FIG. 11) in a normally open switch 316 secured to a bracket 318 mounted on the machine frame 60. To move the arm 293 away from the button 314 the shaft 88 is surrounded by a torsion spring 320 (see FIG. 4), one end of which is connected to the machine frame 60 and the other end of which is connected to a collar 321 on the shaft 88. During the latter part of the last sewing cycle of a seam the shaft 88 is rocked to move the arm 293 rearwardly against the button 314 by the engagement of the cam 74 with the pawl lever 76, closing the switch 316. Closing the switch 316 causes the coil 258 to be energized and the locking thread pull-off lever 210 to be actuated and latched in position. The lever 210 is retained in latched position until the machine is started to sew a new seam. For this purpose the pawl lever 76 is bifurcated along its intermediate portion and straddles a shaft 322 (see FIG. 10) running parallel to the sewing shaft 52 and supporting a sleeve 324 through which a fulcrum pin 326 passes diametrically of the shaft 322, a flat surface on the pawl lever 76 bearing on a lug 328 formed on the arm 78 to transfer rearward motion to the arm when engaged by the pawl lever. When the treadle 64 is depressed to start the machine in operation the rod 302 depresses the cam 68 (see FIGS. 5 and 6) causing the lever 72 to move a forwardly extending arm upwardly against an adjusting screw 330 carried by a laterally extending arm of the pawl lever 76, moving the pawl arm of the lever in a direction along the sewing shaft 52 out of the path of movement of the cam 74. In this way the pawl lever is released for movement toward the shaft, permitting corresponding movement of the arm 78, the lever 82 and the arm 86 which is secured to the shaft 88, under the action of the spring 320. When the arm 293 is moved forwardly away from the button 314, the Bowden wire 282 engages the bolt 278 connected to the latch block 268 (FIG. 9) and moves the block away from the armature 262 to release the locking thread measuring lever 210 for movement into the position shown in FIG. 8 under the action of the spring 238. To maintain the adjusting screw 330 constantly in engagement with the forwardly extending arm of the lever 72 the laterally extending arm of the pawl lever 76 is acted upon by a tension spring 332 stretched between the pawl lever and a pin 334 projecting horizontally from the machine frame 60.

To cause the needle thread pull-off bar 150 to be retained in actuated position while the machine is at rest the rod 182 (FIG. 33) to which the shouldered finger 176 is connected for actuating the bar is held in its for-

ward position by reason of a latch engaging the upper portion of the lever 82 to which the rod is fastened. For this purpose, as more clearly shown in FIG. 5, the upper arm of the lever 82 has a laterally extending lug 336 projecting into the path of movement of a detent 338 (see also FIG. 10) carried by an arm 340 secured to the rearward end of a shaft 342. The shaft 342 is rotatably mounted in a boss portion of the machine frame and has secured to its forward end a horizontal arm 344 (FIG. 5) overlying the horizontal arm of the pawl lever 76. At the end of the horizontal arm 344 is an adjusting screw 346 arranged to engage a surface on the arm of the pawl lever, a spring 348 being stretched between a pin on the arm 344 and the fixed pin 334 to maintain the adjusting screw in engagement with the lever 76. When the machine is brought to rest at the end of a seam the spring 348 causes the detent 338 to engage the side surface on the lug of the lever 82, the lever 82 having been rocked rearwardly at its upper end by the pawl lever 76. Rearward movement of the upper end of the lever 82 actuates the arm 86 also rearwardly, causing the presser foot to be lifted and the needle thread pull-off bar to be actuated to pull off thread.

Upon starting the machine in operation upon a new seam downward movement of the control treadle 64 raises the horizontal arm of the pawl lever 76 disengaging the pawl lever from the cam 74 and simultaneously raising the arm 344 to disengage the detent 338 from the projection on the lever 82, thus releasing the pull-off bar 150 for rearward movement from the dotted line position of FIG. 34 to the solid line position where the measured thread pulled off is available for use by the stitch-forming devices. Thus, the withdrawn thread is released in a length sufficient and in proper time to start a new seam.

To actuate the needle thread nipper jaw 112 as the machine comes to rest and to retain it in actuated position while the machine is at rest and until the first stitch of a new seam has been inserted, the solenoid 256 is energized by an energizing switch 350, shown in the upper parts of FIGS. 4 and 10. The switch is secured to the bracket 318 at the rear of the arm 86 which actuates it. For this purpose the rockshaft 88 has mounted for free swinging movement thereon an arm 352 having a right angle flange overlapping the rearward side of the arm 86 and being arranged to engage a button 354 on the energizing switch 350. The arms 86 and 352 move rearwardly together to actuate the button 354, the arm 352 being connected by a spring 356 stretched between it and a pin 358 on the lever 82 to maintain the swinging arm 352 yieldingly in engagement with the arm 86. However, the arm 86 is moved forwardly before the machine is started in operation by the action of the torsion spring 320 on the rockshaft 88.

In order to prevent opening of the switch 350 before the machine has inserted the first stitch of a new seam the arm 352 is retained in switch button engaging position by a latch 360 rotatably mounted on a screw 362 threaded in an angle plate 363 on the bracket 318. The forward end of the latch 360 has a hooked end co-operating with the upper forward corner of the arm 352 to retain it in its most rearward position, the arm 86 and the rockshaft 88 being released by depressing the control treadle 64. The latch 360 also has pivotally connected to it the rearward end of a link 364, the forward end of which is connected to an arm 366 rotatable about a pin 368 fixed in a slotted block 370 secured to an upper portion of the machine frame. The arm 366 has rotatably mounted upon it a roll 372 engaging a concentric surface of a cam 374 secured to the main sewing shaft 52. The cam 374 has a radially grooved portion into which is inserted a cam block 376 capable of adjustment along the circumference of the cam by reason of a releasable clamp screw 378 passing through a slot 380 in the block and into threaded engagement with the cam 374. The cam block 376 is so located that as soon as

the first stitch of a seam has been inserted in the work the cam roll 372 is moved rearwardly, releasing the arm 352 from the latch 360. After the arm 352 is released from the latch 360 the needle thread is held in the work frictionally to prevent its withdrawal, so that the seam may continue without displacement on the first stitch, even though the nipped jaw 112 releases its grip on the needle thread.

By way of reviewing the operation of the automatic thread severing means and of understanding more readily the circuits for controlling the thread severing operation, reference may be had to FIG. 36 of the drawings. In the illustration of the circuits an alternating current source of power is indicated at 382 and 384, consisting of wires connected to manually operated main line switches 386 and 388 movable in unison through a mechanical interconnection, indicated by the dotted line 390. The line switches 386 and 388 are represented as controlling the flow of current to the schematically indicated components between bus bars 392 and 394. The actual mechanical location of the apparatus is generally that illustrated in FIG. 1 of the drawings, many of the connections being contained in a switch box 396 secured to the machine frame and to connection boxes (not shown) otherwise conveniently arranged on the frame. To indicate closure of the line switches a pilot light 398 is connected between the bus bars 392 and 394.

Immediately below the pilot light 398 is illustrated a heating circuit for the locking thread severing plate 116. Directly connected to the severing plate 116 is the secondary of a step-down transformer 400, the primary of which has one end connected to the bus bar 394 and the other end connected to a normally closed time delay opening relay comprising a pair of contacts 402-TDOC. From the contacts 402-TDOC current flows from either of two hand adjustable rheostats 404 and 406. The rheostat 406 reduces the voltage applied to the transformer 400 to such an extent that the thread severing plate 116 is maintained at a relatively low preheat temperature insufficient to sever the thread, but sufficient to reduce the time required to raise the temperature of the plate to a point where the thread may be severed when brought into contact with it. The rheostat 406 is adjusted to provide a lower resistance than that of the rheostat 404 and to cause the plate 116 to be heated to a high thread severing temperature. The rheostats 404 and 406 are controlled by the energizing switch 312, which is of two-pole, double-throw construction, the movable contact in the switch being biased by a spring 408 to close the circuit through the high heat rheostat 406 while the machine is in stopped position. To preheat the plate 116, the button 310 of the switch 312 is depressed against action of the spring 408 to complete the circuit through the low heat rheostat 404 and the transformer 400, a single throw double pole toggle switch 410 serving to connect the switch 312 to the bus bar 392.

To actuate the time delay opening contacts 402-TDOC, these contacts comprise a relay, the coil for which is indicated at 402-R, having terminals connected between the upper contacts of the energizing switch 312 and the bus bar 394. The switch 312 is shown with the button 310 in its uppermost position for connecting the bus bar 392 through the toggle switch 410 to the high heat rheostat 406 and the relay coil 402-R, the contact 402-TDOC being held open while the machine is at rest by the energization of the coil 402-R so that no current flows through the transformer 400 or the plate 116. As soon as the machine is started in operation the control treadle 64 and the rod 62 are depressed causing the lever 298 to engage the button 310 and to close the circuit through the energizing switch 312 to the preheating rheostat 404. The plate 116 is then raised to a preheat temperature which continues until the machine again comes to rest at the end of a seam. As soon as the treadle 64 is released from the operator's foot the switch 312 moves to the

position shown closing the circuit through the high heat rheostat 406, and contacts 402-TDOC which remain closed for a short predetermined period of time, heating the plate 116 to high, thread severing temperature. The circuit through the high heat rheostat continues for a sufficient time to enable the operator to remove the shoe being operated upon from sewing position in the machine and to engage the locking thread extending from the shoe with the thread severing plate 116. In the circuit illustrated it has been found sufficient to delay the opening of the contacts 402-TDOC for a period of eight seconds.

The circuit for the locking thread measuring pull-off coil 258 is shown in FIG. 36 as being connected in series with the switch 316 so that a measured length of locking thread is pulled off and rendered available only after the machine is restarted in operation on a new shoe, movement of the rockshaft 88 and the arm 90 in a clockwise direction acting through the Bowden wire 282 to actuate the latch block 268 away from the armature for the coil 258. Upon movement of the arm 293 away from the button 314 of the energizing switch 316 a spring 411 opens it.

The circuits for actuating the needle thread nipper jaw 112 and for controlling the current flowing through the needle thread severing plate 94 are similar to those described in connection with the locking thread measuring pull-off and thread severing plate 116. For this purpose the energizing switch 350 is connected in series with the needle thread nipper jaw actuating coil 256, the circuit being completed at the end of a seam just before the machine comes to rest with the arm 352 engaging the button 354 on the switch 350. As soon as the arm 352 has moved to circuit closing position it is retained in this position by the latch 360 and is released from latched position only after the first stitch of a new seam has been inserted in the work. Upon movement of the arm 352 away from the button 354 a spring 412 opens the energizing switch 350.

To control the flow of current through the needle thread severing plate 94, this plate is connected with the secondary of a transformer 413, the primary of which is connected at one end to the bus bar 394, and at the other end to one of a pair of normally closed time delay opening contacts 414-TDOC. During sewing operations the plate 94 is heated to a relatively low preheat temperature insufficient to sever the thread but sufficient to reduce the time required to raise the plate to the required thread severing temperature. For these purposes the contacts 414-TDOC are connected to a hand adjustable pre-heating rheostat 416 energized by the lowermost contacts in the energizing switch 313, in turn actuated against the force of a spring 418 by the lever 298 engaging the button 311. The switch 313 is connected to the bus bar 392 through a manually actuated toggle switch 420. After the seam has been completed the control treadle 64 is released raising the lever 298 opening the circuit to the preheating rheostat 416 and closing the uppermost contacts of the switch 313 to connect a high heat rheostat 422 through the contacts 414-TDOC with the transformer 413. A high thread severing temperature is maintained in the plate 94 for a sufficient period of time to enable severing of the needle thread and the contacts 414-TDOC are thereafter opened. To open the contacts 414-TDOC, these contacts comprise a relay, the coil for which is indicated at 414-R and which is energized as soon as the control treadle is released before bringing the machine to rest. It has been found sufficient to delay the opening of the contacts 414-TDOC for a period of two seconds so that an opportunity may be given to complete the last stitch of a seam and to actuate the needle thread nipper jaw 112.

In the machine of inventor's prior application each loop of needle thread after being withdrawn from the work and opened up for entry of a loop of locking thread is disengaged from the hook of the needle by a projection 75 on a loop spreader, acting during its return move-

ment from spreading the needle loop. Utilizing the return movement of the loop spreader to disengage the thread from the hook of the needle is undesirable for a number of reasons. Such disengagement requires additional motion to be imparted to the loop spreader. Also, at the time the loop spreader acts to disengage the thread from the needle the spreader must be actuated rearwardly further than normally required, so that the locking thread carrying finger 26 must be projected into the spread needle loop sooner in order that the loop spreader may start its rearward movement in time to completely cast the loop from the needle. In addition, return movement of the loop spreader from its fully spread position tends to push the loop rearwardly against the needle, so that in some instances it may be entangled momentarily with the needle barb.

Accordingly a feature of the illustrated machine avoids the difficulties inherent in the prior machine by providing an arm 423 (see FIGS. 2, 12 and 25) separate from any of the other stitch-forming devices for retracting each loop of needle thread and for casting it off the needle hook through entry into each spread needle loop from that side opposite to the completed stitches of a seam being inserted. Because the retracting arm enters each loop from the side opposite to the completed stitches, its actuation may start before the spreader has moved rearwardly to its fully retracted position. In casting off the needle loop from the needle the retracting arm 423 urges the loop to a position where it falls naturally during its contraction about the entrapped loop of locking thread, as illustrated in FIG. 27, thus maintaining a constant and more uniform control over the movements of the needle thread after being cast off and permitting freer contraction about the entrapped locking thread than with previous machines of this type.

To improve the cast-off action the present retracting arm 423 is formed with a substantially vertical shank and a terminal 424 bent laterally at an obtuse angle (FIG. 12) to the shank in the direction of the completed stitches in a seam, the bent terminal acting in a spade-like manner to lift the thread from the needle hook with a continuous movement after engaging the thread. The terminal also is flattened to distribute the pressure along a substantial section of the thread, avoiding damage to the thread and is inclined downwardly so that the thread once having been freed from the needle hook may be drawn rapidly through the work against the locking loop without being caught on the arm 423. By this arrangement a more uniform movement of the needle thread loop results than with prior machines. For these reasons less variation occurs in the formation and setting of successive stitches in the work than has been possible heretofore.

For actuating the needle loop retracting arm 423 its upper end is secured in a clamp 426 (see FIGS. 12 and 25). The clamp 426 consists of a slotted block across the slot of which passes a clamp screw 428 and through a perforation in which passes a rockshaft 430 rotatably mounted in bearings in a bracket 432 attached to the frame 60 of the machine. The bearings project upwardly from a forward portion of the bracket 432 and are disposed at opposite sides of the clamp 426. Also, between bearings of the bracket 432 for the rock shaft is a clamp collar 434 (FIG. 25) for preventing displacement of the shaft 430 lengthwise. At the rearward end of the shaft is an integral U-shaped arm 436 having at its lower end a roll 438 engaging a cam groove in a sector 440 secured to a shaft 442 arranged in bearings in the bracket 432 at right angles to and beneath the retracting arm shaft 430. The shaft 442 also serves to support the loop spreader 6, the upper end of which passes through a diametrical opening in the shaft 442 and which is held in position therein by a set screw 444 threaded axially into the end of the shaft 442.

The cam groove in the sector 440 is so shaped that the terminal on the needle loop retracting arm 423 remains

stationary until the loop spreader is moved out of each needle loop, and then the retracting arm engages and lifts the upper portion of the spread needle loop as the loop spreader 6 approaches the broken line position 6A of FIG. 25. At the same time the needle loop is lifted from the needle hook, the loop spreader moves quickly rearwardly until its lower end is inside the arcuate path of the needle at the position 6A, thus completely freeing the needle loop for contraction about the locking thread.

To actuate the loop spreader 6 the shaft 442 has secured to its right-hand end a forked arm 446 (FIGS. 12 and 25) within the work of which is pivotally connected a link 448 similarly connected to an arm of a lever 450 driven by a cam on the upper sewing shaft 54. The mechanism for the loop spreader, thus briefly referred to, is more fully described in the prior application above identified.

A particularly desirable result in the operation of the needle loop retracting arm 423, as described, is in its manner of co-operation with the needle thread nipper jaw 112 and with the means for severing the needle thread at the end of a seam inserted in a shoe outsole. During the first sewing cycle of a new seam the end of the needle thread is clamped by the nipper jaw, as shown in FIG. 25. During this first sewing cycle the needle and loop spreader enlarge the loop of needle thread to the solid line position of this figure while the nipper jaw 112 retains its grip on the thread, the needle loop retracting arm 423 being held stationary at this time and the needle moving away from the work to the solid line position of FIG. 25. At this position of the needle the nipper jaw 112 releases the end of the needle thread, and the take-up 16 continues to give up thread in the proper amount to enable the needle loop to expand nearly to the broken line position with the spreader in the position 6B. However, at this time the take-up 16 reduces the amount of needle thread given up, causing the thread end to be drawn from the position of FIG. 25 to that of FIG. 26, in the direction of the arrow 452, so that the end of the needle thread is concealed within the work and requires no trimming after the seam is completed. At the completion of the first stitch in a seam the locking thread is drawn by the contracting needle loop against the work and properly set within the work so that no trimming of the locking thread is required. Even if the first stitch of a seam is not fully tensioned because of an unsecurely held free end of needle thread, no difficulty is encountered ordinarily in the manufacture of a shoe for this reason, since the first stitch of a new seam is located within the heel area of a shoe. Upon the application of a heel any visible surplus in the locking thread exposed outside the sole is accordingly covered up. During the continued formation of the first stitch after the solid line position of the needle loop in FIG. 25 is reached the uniformity of control afforded by the loop retractor arm 423 is adequate to prevent displacement of the needle thread end from the position of FIG. 26 as the needle loop is drawn with the locking thread into the sole. With previous types of needle loop retracting devices such uniformity of needle loop retraction has not been possible.

In order to simplify the construction and ease of replacement for the heated needle thread severing plates a quickly removable form of plate is employed as best shown in FIGS. 37 to 45. To accommodate the quickly removable thread severing plate the work support also has been modified. Referring to the figures noted, the modified work support is indicated at 454 and instead of having a threaded opening to receive a clamp screw for the thread severing plate the work support 454 has an unthreaded opening 456 within which fits a circular boss 458 (FIG. 44) projecting downwardly at right angles from one arm of a plate 460. The boss 458 may be inserted into the opening 456 where it is electrically and mechanically secured by sweating. To prevent rotation of the plate 460 about the center of the boss 458 the

other arm of the plate has an opening 462 fitting a headed fiber insulating plug 464 engaged with a second opening 466 formed in the work support, the area of the work support around the second opening 466, as well as the walls of the slot through which the plate 460 projects, being covered with a layer of baked-on porcelain material 468 to insulate the adjacent portions of the thread severing plate 460.

In place of the simple soldering lug on the previously described form of thread severing plate, the improved plate 460, illustrated in FIG. 44, has a perforated soldering enlargement 470 into which passes the end of a circuit connecting wire 472. Both the boss and the connecting wire are thus soldered in place in the opening 456 of the work support and in the enlargement of the severing plate 460.

To protect the heated base of the improved thread severing plate 460 from contact with the work, the work support 454 has two additional openings 474 at either side of its needle opening, indicated at 476, to receive angularly bent tangs 478 (see FIG. 39) at the ends of a quickly replaceable spring guard strip 480. Along the underside of the strip 480 between the tangs it is covered with a baked-on refractory porcelain coating 482 to insulate it electrically from the thread-severing plate. The strip 480 serves not only to protect the heated plate 460 from contact with the work but also to provide a quickly replaceable support for the work along the inner edge of the needle opening 476, the work support 454 being cut away at 484 (FIG. 38) along an area directly behind the left end of the opening 476 through which the needle passes during its work penetrating stroke. Thus, in case the needle is deflected rearwardly as occasionally happens into engagement with the strip 480, the strip may readily be replaced and no damage will be inflicted on the more expensive construction of the work support. The strip 480 has sufficient resiliency to enable these tangs to be spread apart while being inserted in the opening 474, thus frictionally holding the strip in place. Since the pressure of the work on the strip 480 is always downwardly while the work support and presser foot are acting to clamp and feed the work, there is no possibility for displacement of the strip.

In the machine of my prior application the locking thread carrying finger 26 is mounted on a carrier connected for movement with the presser foot as the presser foot is shifted to engage and clamp work, which varies in thickness from one stitch to another. By this means the locking thread-carrying finger is maintained at a uniform distance above the work-engaging portion of the presser foot and swings along a path forming an acute angle with the plane of each triangular needle loop as spread by the loop spreader, from a position outside the arc of needle curvature. As a result, the locking thread-carrying finger in its idle position projects forwardly from the point of needle operation, forming somewhat of a hazard for an operator, and occasionally providing an obstacle to proper presentation of a shoe to the machine, especially where it is necessary to tilt a shoe upwardly in sewing abruptly curving portions along extremely deep shanks.

In the machine of the present invention it has been found possible to avoid the hazards and the obstacles of the prior locking thread-carrying finger and to provide a finger which will be effective in forming the first stitch of a new seam more effectively than has been possible heretofore, especially where the end of locking thread is relatively short in forming the first stitch of a new seam so that no trimming is required as with the thread severing system of the present invention. The present improved locking thread-carrying finger 26, therefore, not only enters each spread loop of needle thread at a uniform distance above the presser foot but moves along a path forming an acute angle with the plane of the triangular spread needle loop at the side of the completed stitches

in a seam. Thus, the finger 26 enters each needle loop from within the arc of needle curvature, rather than from outside the curvature of the needle, as in the prior machine. In this way the locking thread-carrying finger is retracted from each needle loop rearwardly into the machine, so that in its idle position it does not form a hazard or otherwise present an objectionable obstacle at the front of the machine to the proper presentation of the shoe.

Referring more particularly to FIG. 29, it will readily be apparent that the improved locking thread-carrying finger moves from its idle rearward position, indicated by the broken lines, to the solid line forward position where it enters each loop of needle thread, the forward movement being along a path indicated by the dot-dash line 486. The path of the finger 26 thus forms an acute angle 488 with the plane of the spread triangular needle loop at the side of the completed stitches in a seam. For this purpose the locking thread-carrying finger is secured by a clamp screw 490 (see FIGS. 12, 13 and 14) entering a socket at the lower end of an arm 492. The arm 492 is mounted for swinging movement about a pin 494 passing through the upper end of the arm 492, through the arm 120 and across a slot formed in the arm 120, which arm 120 is movable with the presser foot 14.

Instead of utilizing a carrier for the locking thread-carrying finger 26 separate from the presser foot and connecting the carrier with the presser foot, as in the prior machine, the arm 120 of the present machine is clamped directly to a fulcrum pin 496 rotatably supported in a feed carrier for the work support and the presser foot. The fulcrum pin 496 also has clamped to it the presser foot, so that vertical movements of the presser foot are transferred to the arm 120 directly to the locking thread-carrying finger 26.

To actuate the locking thread-carrying finger 26 toward and from each needle loop the arm 492 has secured to it a ball headed stud 498 surrounded by a socket at one end of a link 500, having at its opposite end a similar socket surrounding a ball headed stud integral with an arm of a lever 502. The lever 502 is rotatable at the lower end of an inclined pin 504 (see FIG. 12) secured at its upper end in the arm 120. The lever 502 is actuated in a manner more fully described in the prior application through a link 505 (FIGS. 2 and 3) and other connections driven by a cam on the sewing shaft 54.

Not only is it possible to eliminate hazards to the operator as a result of a forwardly projecting locking thread carrying finger and obstacles resulting from the presence of the finger in its idle position at the front of the machine, but in the present machine the locking loop detaining finger 28, which is mounted to enter each loop of needle thread and to engage the work in line with the seam may be adjusted to form its indentation 46 (FIG. 30) in the upper surface of the work in line with the seam more accurately, as the result of mounting on the locking thread-carrying finger, so that the indentation will be covered more uniformly and reliably by each later formed stitch. This result is secured in the present machine because the relationship of the locking thread-carrying finger and the loop detaining finger 28 is opposite to that in the prior machine, the present locking thread carrying finger having its concave curvature facing forwardly in the present machine, whereas in the prior machine its concave curvature faces rearwardly. For this reason it is possible to adjust the point of engagement of the detaining finger more accurately in the present machine partly because of improved visibility and partly because of less interference between the two fingers 26 and 28, than in the prior machine.

Preferably, the tension in the locking thread in the present machine is relieved as each stitch is being set in the work by the take-up, so that as each needle loop draws its entrapped loop of locking thread into the work there will be no danger of disengagement of the locking loop from the needle loop or from any other nonuni-

formity in operation. Accordingly, the locking thread 44 between the arms of the U-shaped bar 212 is engaged by a flanged roll 506 rotatably mounted upon a bolt 508 carried by the upper end of a locking thread controller arm 510, best shown in FIGS. 2, 3, and 35. The arm 510 extends upwardly from a hub portion within which is secured a rockshaft 512 (FIG. 3). The rockshaft 512 is rotatably mounted within bearings formed by a pair of forwardly projecting lugs 514 on the machine frame. Between the lugs 514 the shaft 512 has secured to it a rearwardly extending arm 516 pivotally connected to a downwardly extending link 518, the lower end of which is similarly connected to a needle guide actuating bell crank 520 constructed and operating in the same manner as that indicated at 73 in United States Letters Patent No. 1,169,906, granted February 1, 1916, upon application of Fred Ashworth. The bell crank 520 is actuated by a cam on the sewing shaft 54 and is mounted for oscillation with a shaft 522 rotatable in the machine frame. At the forward end of one arm the bell crank 520 is provided with a toothed segment meshing with the teeth of a pinion 524 rotatable in the machine frame and operatively connected to a needle guide 526 movable along the needle to stiffen it as it enters the work. The arrangement is such that when the needle is penetrating the work, the needle guide moves with the needle and the controller spool 506 deflects the thread between the arms of the U-shaped bar 212 to withdraw thread from the locking thread supply 214.

To avoid retraction of locking thread from the previously formed stitch in the work while the controller arm 510 is operating, the hub of the arm 510 has secured to it an angular cam plate 528 (see FIG. 2), the left end of which engages a swinging dog 530 rotatably mounted on a stud 532 mounted for swinging movement in the frame of the machine. The locking thread 44 passes between a curved surface on the dog 530 and a side of the right hand bearing lug 514 in such a way that when pressed toward the lug the dog grips the locking thread against it and prevents thread movement from the last formed stitch in the work. The shape of the cam plate 528 is such that the locking thread is gripped while the controller arm is acting to draw thread from the supply. When the controller arm moves forwardly away from its thread deflecting position the dog 530 releases its grip on the thread so that slack is provided during the time each stitch is being set by the take-up. By actuating the controller arm 510 through connections with the needle guide actuating bell crank, a more effective operation is obtainable in the locking thread controller arm in providing slack thread than in the machine of the prior application, the controller arm of that application being actuated through connections with the loop spreader.

The nature and scope of the invention having been indicated and a particular embodiment with modifications having been described, what is claimed is:

1. A sewing machine having a main frame, stitch-forming and work-feeding devices in the frame, including a hook needle for carrying through a work piece loops of thread having a substantially reduced tensile strength when heated to a predetermined temperature, and means for interlocking the thread loops carried through the work by the needle to form a seam, means including a presser foot and a work support having a needle opening through which the needle and thread pass for clamping the work piece while being operated upon by the needle, and mechanisms for actuating the stitch-forming and work-feeding devices and presser foot in timed relationship to each other, in combination with means for enabling the thread to be severed by a pull exerted against the last formed stitch in a seam, comprising a member fixed to the work support, exposed within the needle opening and in a position to be engaged by the thread and heated above said predetermined temperature.

2. A sewing machine having a main frame, stitch-form-

ing and work-feeding devices in the frame, including a hook needle for carrying through a work piece loops of thread having a substantially reduced tensile strength when heated to a predetermined temperature, and means for interlocking the thread loops carried through the work by the needle to form a seam, means for clamping the work piece while being operated upon by the needle, and mechanisms for actuating the stitch-forming and work-feeding devices in timed relationship to each other, in combination with means mounted close to a surface of the work piece while engaging the clamping means for enabling the thread to be severed by a pull exerted against the last formed stitch in a seam, comprising a member heated above said predetermined temperature, and a nipper jaw mounted for movement on the work-clamping means for deflecting the thread into engagement with the heated member.

3. A sewing machine having a main frame, stitch-forming and work-feeding devices in the frame including a hook needle for carrying through a work piece loops of thread having a substantially reduced tensile strength when heated to a predetermined temperature and means for interlocking the thread loops carried through the work piece by the needle to form a seam, means for clamping the work piece while being operated upon by the needle, a take-up for giving up thread to the stitch-forming devices and for setting each stitch in the work piece, a thread lock against which each stitch is set by the take-up, and mechanisms for actuating the stitch-forming and work-feeding devices in timed relationship to each other, in combination with means mounted close to a surface of the work piece while engaging the clamping means for enabling the thread to be severed by a pull exerted against the last formed stitch in a seam while the thread lock is gripping the thread, comprising a member engaged by the thread and heated above said predetermined temperature and a nipper jaw mounted for movement on the work-clamping means for deflecting the thread into engagement with the heated member.

4. A shoe sewing machine having a main frame, stitch-forming and work-feeding devices in the frame including a hook needle for carrying through a work piece loops of thread having a substantially reduced tensile strength when heated to a predetermined temperature and means for interlocking the thread loops carried through the work piece by the needle with another thread to form a seam, means for clamping the work piece while being operated upon by the needle, and mechanisms for actuating the stitch-forming and work-feeding devices in timed relationship to each other, in combination with means mounted close to the surface of the work piece while engaging the clamping means for enabling the needle thread to be severed by a pull exerted against the last formed stitch in a seam, comprising a member engaged by the thread and heated above said predetermined temperature, and means mounted further away from the surface of the work piece while engaging the clamping means for enabling the locking thread to be severed after severing the needle thread, comprising a member supported on the machine frame at a position convenient for engagement with the locking thread and heated above said predetermined temperature.

5. In a sewing machine having a main frame, stitch-forming and work-feeding devices in the frame including a hook needle for carrying through a work piece loops of thread having a substantially reduced tensile strength when heated to a predetermined temperature and means for interlocking the needle thread loops carried through the work piece to form a seam, means including a work support and a presser foot for clamping the work piece while being operated upon by the needle and mechanisms for actuating the stitch-forming and work-feeding devices in timed relationship to each other, in combination with means mounted close to a surface of the work piece while engaging the work support for enabling the thread to be severed by a pull exerted against the last locked portions

of the thread in a seam, comprising a member heated above said predetermined temperature, a nipper jaw mounted for movement on the work support for deflecting the thread into engagement with the heated member and a shoulder on the work support located along a path taken by the thread between the heated member and the stitch-forming devices, against which shoulder the thread is gripped after being deflected by the nipper jaw.

6. A sewing machine having a main frame, stitch-forming and work-feeding devices in the frame, including a needle for carrying through a work piece loops of thread having a substantially reduced tensile strength when heated to a predetermined temperature, and means for interlocking the thread loops carried through the work by the needle to form a seam, means for clamping the work piece while being operated upon by the needle, and mechanisms for actuating the stitch-forming and work-feeding devices in timed relationship to each other, in combination with means mounted close to a surface of the work piece while engaging the clamping means for enabling the thread to be severed by a pull exerted against the last formed stitch in a seam, comprising an electrical resistance member heated above said predetermined temperature at the end of a seam and engaged by the thread, and a circuit for maintaining the temperature of the electrical resistance member below the said predetermined temperature to prevent injury to the thread during the major portion of each seam.

7. A sewing machine having a main frame, a sewing shaft in the frame, stitch-forming and work-feeding devices driven from the sewing shaft including a needle for carrying through a work piece loops of thread having a substantially reduced tensile strength when heated to a predetermined temperature and means for interlocking the thread loops carried through the work piece by the needle to form a seam, means for clamping the work piece while being operated upon by the needle, driving and stopping mechanisms for the sewing shaft and an operator controlled treadle connected to the driving and stopping mechanism to start and stop the sewing shaft, in combination with means mounted close to a surface of the work piece while engaging the clamping means for enabling the thread to be severed by a pull exerted against the last formed stitch in a seam, comprising an electrical resistance member engaged by the thread, a circuit for maintaining the temperature of the electrical resistance member below said predetermined temperature during a major portion of sewing operations, and an energizing switch in the circuit operatively connected to the treadle for the driving and stopping mechanism to open the circuit when the treadle is released in stopping the sewing shaft and to close the circuit whenever the treadle is depressed to start the sewing shaft.

8. A sewing machine having a main frame, a sewing shaft in the frame, stitch-forming and work-feeding devices driven from the sewing shaft including a needle for carrying through a work piece loops of thread having a substantially reduced tensile strength when heated to a predetermined temperature and means for interlocking the thread loops carried through the work piece by the needle to form a seam, means for clamping the work piece while being operated upon by the needle, driving and stopping mechanisms for the sewing shaft and an operator controlled treadle connected to the driving and stopping mechanism to start and stop the sewing shaft in combination with means mounted close to a surface of the work piece while engaging the clamping means for enabling the thread to be severed by a pull exerted against the last formed stitch in a seam, comprising an electrical resistance member engaged by the thread, a first circuit for maintaining the temperature of the electrical resistance member below said predetermined temperature during a major portion of sewing operations, a second circuit for heating the electrical resistance member to said predetermined temperature, an energizing switch in the circuit operatively connected to the treadle for the driving

and stopping mechanism to open the first circuit and close the second circuit when the treadle is released in stopping the sewing shaft and to close the first circuit whenever the treadle is depressed to start the sewing shaft, and a time delay relay for opening the second circuit through said switch to the electrical resistance member after the release of the treadle.

9. A sewing machine having a main frame, stitch-forming and work-feeding devices in the frame, including a needle for carrying through a work piece loops of thread having a substantially reduced tensile strength when heated to a predetermined temperature, and means for interlocking the thread loops carried through the work by the needle to form a seam, means for clamping the work piece while being operated upon by the needle, and mechanisms for actuating the stitch-forming and work-feeding devices in timed relationship to each other, in combination with means mounted close to a surface of the work piece while engaging the clamping means for enabling the thread to be severed by a pull exerted against the last formed stitch in a seam, comprising an electrical resistance member heated above said predetermined temperature and engaged by the thread, a circuit for maintaining the temperature of the electrical resistance member below the said predetermined temperature to prevent injury to the thread during the major portion of each seam, and means for increasing the flow of current through the electrical resistance member at the time the treadle is released to heat it above the predetermined temperature.

10. A sewing machine having a main frame, stitch-forming and work-feeding devices in the frame, including a needle for carrying through a work piece loops of thread having a substantially reduced tensile strength when heated to a predetermined temperature, and means for interlocking the thread loops carried through the work by the needle to form a seam, means for clamping the work piece while being operated upon by the needle, and mechanisms for actuating the stitch-forming and work-feeding devices in timed relationship to each other, in combination with means mounted close to a surface of the work piece while engaging the clamping means for enabling the thread to be severed by a pull exerted against the last formed stitch in a seam, comprising a member heated above said predetermined temperature, an electrical resistance member engaged by the thread, a circuit for maintaining the temperature of the electrical resistance member below the said predetermined temperature to prevent injury to the thread during the major portion of each seam, means for maintaining a flow of current through the electrical resistance member during the time the treadle is depressed to heat it below the predetermined temperature, including a variable high resistance, and a variable low resistance for controlling the current through the resistance member after the treadle is released to stop the sewing shaft.

11. A sewing machine having a main frame, a sewing shaft in the frame, stitch-forming and work-feeding devices driven from the sewing shaft, including a hook needle for carrying through a work piece loops of thread having a substantially reduced tensile strength when heated at a predetermined temperature and means for interlocking the thread loops carried through the work piece by the needle with other thread to form a seam, means for clamping the work piece while being operated upon by the stitch-forming devices, driving and stopping mechanisms for the sewing shaft and a treadle for controlling the operation of the driving and stopping mechanisms, in combination with means mounted close to a surface of the work while engaging the clamping means for enabling the locking thread to be severed by a pull exerted on the last formed stitch in a seam, comprising an electrical resistance member heated above said predetermined temperature, a circuit for heating the electrical resistance member including a switch operatively connected to the

treadle for closing the circuit when the treadle is released, and a thread measuring member for deflecting the locking thread to hold aside a length of thread sufficient in length to insure starting of a new seam, a coil for actuating the thread-measuring member, and a switch connected to the driving and stopping mechanism for closing the circuit to the thread measuring member coil during the last few degrees of rotation of the sewing shaft at the end of a seam.

12. A sewing machine having a main frame, a sewing shaft in the frame, stitch-forming and work-feeding devices driven from the sewing shaft, including a hook needle for carrying through a work piece loops of thread having a substantially reduced tensile strength when heated at a predetermined temperature and means for interlocking the thread loops carried through the work piece by the needle with other thread to form a seam, means for clamping the work piece while being operated upon by the stitch-forming devices, driving and stopping mechanisms for the sewing shaft and a treadle for controlling the operation of the driving and stopping mechanisms, in combination with means mounted close to a surface of the work while engaging the clamping means for enabling the locking thread to be severed by a pull exerted on the last formed stitch in a seam, comprising an electrical resistance member heated above said predetermined temperature, a circuit for heating the electrical resistance member including a switch operatively connected to the treadle for closing the circuit when the treadle is released, and a thread measuring member for deflecting the locking thread to hold aside a length of thread sufficient in length to insure starting of a new seam, a coil for actuating the thread measuring member, a switch connected to the driving and stopping mechanism for closing the circuit to the thread measuring member coil during the last few degrees of rotation of the sewing shaft at the end of a seam, and a latch operatively connected to the driving and stopping mechanism controlling treadle for holding the thread measuring member in thread deflecting position until the treadle is depressed in starting a new seam.

13. A sewing machine having a main frame, a work support on the frame, stitch-forming and work-feeding devices in the frame including a hook needle for carrying through a work piece loops of thread having a substantially reduced tensile strength when heated to a predetermined temperature and means for interlocking the thread loops carried through the work piece by the needle to form a seam, and means including a presser foot for clamping the work piece on the work support while being operated upon by the needle, in combination with means mounted on the work support close to a surface of the work piece while clamped for enabling the thread to be severed by a pull exerted against the last formed stitch in a seam comprising an electrical resistance member, one end of which is electrically connected and fixedly secured to the work support, and a circuit for heating the electrical resistance member connected to the other end thereof.

14. A sewing machine having stitch-forming devices and a work support, in combination with an integral electrically heated thread severing member comprising a U-shaped plate, one arm of which is in the form of a lug connected electrically and secured fixedly to the work support, and the other arm of which is in the form of a lug connected electrically to a heating circuit.

15. A sewing machine having stitch-forming devices and a work support, in combination with an integral electrically heated thread severing member comprising a U-shaped plate, one arm of which is in the form of a lug connected electrically and secured fixedly to the work support, and the other arm of which is in the form of a lug connected electrically to a heating circuit and a layer of insulation between the heating circuit lug and the work support.

16. An integral electrically heated thread severing

member for a sewing machine, comprising a U-shaped plate, one arm of which is in the form of a perforated lug for releasable electrical and physical securement to a work support, the other arm of which is in the form of a soldering lug for electrical connection to a heating circuit and the base of which between the arms is of smaller cross section than the arms to induce concentrated heating.

17. A work support for a shoe sewing machine having a shoe engaging surface intersected by a needle opening and a slot entering the needle opening from one side, in combination with an integral electrically heated thread severing member, comprising a U-shaped plate with its base disposed within the slot, one arm of which plate is in the form of a lug connected electrically and secured fixedly to the shoe engaging surface and the other arm of which is in the form of a lug connected electrically to a heating circuit, a layer of insulation secured between the heating circuit lug and the work support outside said slot, the exposed base portion of the plate being of smaller cross section than the arms to concentrate the heat of said member along the portion disposed within the slot.

18. A work support for a shoe sewing machine having a shoe engaging surface intersected by a needle opening and a slot entering the needle opening from one side, in combination with an integral electrically heated thread severing member, comprising a U-shaped plate with its base disposed within the slot, one arm of which plate is in the form of a lug connected electrically and secured mechanically to the shoe engaging surface and the other arm of which is in the form of a lug connected electrically to a heating circuit, a layer of insulation secured between the heating circuit lug and the work support outside said slot, the exposed base portion of the plate being of smaller cross section than the arms to concentrate the heat of said member along the portion disposed within the slot, said work support being formed with a shoulder at the opposite side of the severing member from the shoe engaging surface of the work support and a nipper jaw pivotally mounted on the shoe support for movement toward and from the shoulder to deflect thread running through the needle opening in the work support into engagement with the severing member and thereafter to grip the thread against the shoulder with a single continuous movement.

19. A sewing machine having a work support, in combination with an integral electrically heated thread severing member comprising a two-armed plate, one arm of which has a boss fitting within an opening in the work support, connected electrically and secured fixedly within said opening in the work support, and the other arm of which is in the form of a lug connected electrically to a heating circuit.

20. A sewing machine having a work support, in combination with an integral electrically heated thread severing member comprising a two-armed plate, one arm of which has a boss fitting within an opening in the work support, connected electrically and secured mechanically within said opening in the work support and the other arm of which is in the form of a lug connected electrically to a heating circuit, and a guard to protect the heated thread severing member from contact with the work, said guard comprising a spring member provided with angular bent tangs entering other openings in the work support for holding the guard in place.

21. A sewing machine having a work support, in combination with an integral electrically heated thread severing member comprising a two-armed plate, one arm of which has a boss fitting within an opening in the work support, connected electrically and secured mechanically within said opening in the work support and the other arm of which is in the form of a lug connected electrically to a heating circuit, and a guard to protect the heated thread severing member from contact with the work, said guard comprising a spring member provided with angular bent tangs entering other openings in the work sup-

port for holding the guard in place, said guard having a refractory coating to insulate it electrically from the thread severing member.

22. A sewing machine having a work support, in combination with an integral electrically heated thread severing member comprising a two-armed plate, one arm of which has a boss fitting within an opening in the work support, connected electrically and secured mechanically within said opening in the work support and the other arm of which is in the form of a lug connected electrically to a heating circuit, and an insulating plug passing through the thread severing member close to the electrically connecting lug and into another opening in the work support to prevent rotation of the plate about the center of the boss.

23. A loop lock stitch sewing machine having a hook needle operating to enter and to withdraw with a loop of thread from work operated upon, a loop spreader acting upon each needle loop withdrawn from the work while engaged with the needle hook to open the loop into a plane intersecting the line of the seam being inserted in the work, devices for interlocking each loop of needle thread with a loop of locking thread and for setting each stitch in the work, in combination with a needle loop retracting arm for casting off the thread carried by the needle hook, arranged to enter each spread loop of needle thread from the side of the loop opposite to the completed stitches of the seam.

24. A loop lock stitch sewing machine having a hook needle operating to enter and to withdraw with a loop of thread from work operated upon, a loop spreader acting upon each needle loop withdrawn from the work while engaged with the needle hook to open the loop into a plane intersecting the line of the seam being inserted in the work, devices for interlocking each loop of needle thread with a loop of locking thread and for setting each stitch in the work, in combination with a needle loop retracting arm for casting off the thread carried by the needle hook, said retracting arm having a shank and a terminal bent from the shank at an obtuse angle in the direction of the completed stitches of the seam to enter and to engage the spread loop of thread between the needle and the spreader and to lift the thread from the needle hook.

25. A lock stitch sewing machine having a hook needle operating to enter and to withdraw with a loop of thread from a work piece operated upon, a loop spreader acting upon each needle loop retracted from the work piece while engaged by the needle hook to open the loop into a plane intersecting the line of the seam inserted in the work piece, devices for interlocking each loop of needle thread with a locking thread and for setting each stitch in the work piece and a shaft on which the loop spreader is mounted for movement toward and from each loop withdrawn from the work piece by the needle, in combination with a needle loop retracting arm for casting off the thread carried by the needle hook, mechanism for actuating the retracting arm comprising a cam on the loop spreader shaft, a shaft on which the retracting arm is mounted, disposed at an angle to the loop spreader shaft and a follower on the retracting arm shaft engaging the cam to cause the retracting arm to enter each spread loop of needle thread from that side opposite to the completed stitches of the seam.

26. A loop lock stitch shoe sewing machine having a curved hook needle operating to enter the work and to withdraw to a fixed position with a loop of thread, means including a loop spreader for opening each loop of needle thread into a uniform triangular shape, the plane of which is disposed at right angles to the line of the seam inserted, a work support toward which the needle operates and against which a work piece is pressed by the work entering thrust of the needle, and a presser foot acting at the side of the work piece from which the needle thrust

is exerted to clamp the work piece against the work support, in combination with means including a locking thread carrying finger connected for movement with the presser foot as it clamps work pieces of different thicknesses to enter each spread loop of needle thread at a uniform distance from the pressure foot along a path forming an acute angle with the plane of the triangular needle loop from the side of the completed stitches in the seam and from within the arc of the needle curvature.

27. A loop lock stitch shoe sewing machine having a curved hook needle operating to enter the work and to withdraw to a fixed position with a loop of thread, means including a loop spreader for opening each loop of needle thread into a uniform triangular shape, the plane of which is disposed at right angles to the line of the seam inserted, a work support toward which the needle operates and against which a work piece is pressed by the work entering thrust of the needle, and a presser foot acting at the side of the work piece from which the needle thrust is exerted to clamp the work piece against the work support, in combination with means including a locking thread carrying finger connected for movement with the presser foot as it clamps work pieces of different thicknesses to enter each spread loop of needle thread at a uniform distance from the pressure foot along a path forming an acute angle with the plane of the triangular needle loop from the side of the completed stitches in the seam and from within the arc of the needle curvature.

28. A loop lock stitch shoe sewing machine having a curved hook needle operating to enter the work and to withdraw to a fixed position with a loop of thread, means including a loop spreader for opening each loop of needle thread into a uniform triangular shape, the plane of which is disposed at right angles to the line of the seam inserted, a work support toward which the needle operates and against which a work piece is pressed by the work entering thrust of the needle, and a presser foot acting at the side of the work piece from which the needle thrust is exerted to clamp the work piece against the work support, in combination with means including a locking thread carrying finger connected for movement with the presser foot as it clamps work pieces of different thicknesses to enter each spread loop of needle thread at a uniform distance from the pressure foot along a path forming an acute angle with the plane of the triangular needle loop from the side of the completed stitches in the seam and from within the arc of the needle curvature, a detaining finger mounted to enter each loop of locking thread from the side opposite the completed stitches, and means for actuating the detaining finger to engage the work piece in line with the seam at the opposite side of the triangular loop, to form an indentation in the work piece in line with the seam which will be covered by later formed stitches.

29. A loop lock stitch shoe sewing machine having a curved hook needle operating to enter the work and to withdraw to a fixed position with a loop of thread, means including a loop spreader for opening each loop of needle thread into a uniform triangular shape, the plane of which is disposed at right angles to the line of the seam inserted, a work support toward which the needle operates and against which a work piece is pressed by the work entering thrust of the needle, and a presser foot acting at the side of the work piece from which the needle thrust is exerted to clamp the work piece against the work support, in combination with means including a locking thread carrying finger connected for movement with the presser foot as it clamps work pieces of varying thickness to enter each spread loop of needle thread at a uniform distance from the pressure foot along a path forming an acute angle with the plane of the triangular needle loop from the side of the completed stitches in the seam and from within the arc of the needle curvature, and a take-up for drawing each loop of needle thread into the work piece to set the stitches, a detaining finger mounted to enter each loop of locking thread from the side opposite the completed stitches, and means for actuating the detaining finger to engage the work piece in line with the seam at the opposite side of the triangular needle loop and to withdraw from the locking loop before the needle loop is drawn into the work piece to set each stitch by the take-up.

30. A loop lock stitch shoe sewing machine having a curved hook needle operating to enter the work and to withdraw to a fixed position with a loop of thread, means including a loop spreader for opening each loop of needle thread into a uniform triangular shape, the plane of which is disposed at right angles to the line of the seam inserted, a work support toward which the needle operates and against which a work piece is pressed by the work entering thrust of the needle, and a presser foot acting at the side of the work piece from which the needle thrust is exerted to clamp the work piece against the work support, in com-

31

bination with means including a locking thread carrying finger connected for movement with the presser foot as it clamps work of varying thickness to enter each spread loop of needle thread at a uniform distance from the presser foot along a path forming an acute angle with the plane of the triangular needle loop from the side of the completed stitches in the seam and from within the arc of the needle curvature, and a take-up for drawing each loop of needle thread into the work piece to set the stitches, a detaining finger mounted to enter each loop of locking thread from the side opposite the completed stitches, means for actuating the detaining finger to engage the work piece in line with the seam at the opposite side of the triangular needle loop and to withdraw from the locking loop before the needle loop is drawn into the work piece to set each stitch by the take-up, and means for relieving the tension in the locking thread before each stitch is set in the work piece by the take-up.

30. A loop lock stitch shoe sewing machine having stitch-forming devices, including a curved hook needle operating to enter a work piece and to withdraw to a fixed position with a loop of thread, a movable needle guide to stiffen the needle, means including a loop spreader for opening each loop of needle thread into a uniform triangular shape, a work support toward which the needle operates and against which the work piece is pressed by the work-entering thrust of the needle, a presser foot acting at the side of the work piece from which the needle thrust is exerted to clamp the work piece against the work support, a locking thread-carrying finger connected for movement with the presser foot as it clamps a work piece of varying thickness to enter each spread loop of needle thread at a uniform distance from the presser foot, a needle thread take-up for giving up thread to the loop spreader and for setting each stitch in the work piece, and mechanisms for actuating the stitch forming devices in proper timed relationship, in combination with locking thread controller means for relieving the tension in the locking thread before each stitch is set in the work piece by the take-up.

31. A loop lock stitch shoe sewing machine having stitch-forming devices, including a curved hook needle operating to enter a work piece and to withdraw to a fixed position with a loop of thread, a movable needle guide to stiffen the needle, means including a loop spreader for opening each loop of needle thread into a uniform triangular shape, a work support toward which the needle operates and against which the work piece is pressed by the work-entering thrust of the needle, a presser foot acting at the side of the work piece from which the needle thrust is exerted to clamp the work piece against the work support, a locking thread-carrying finger connected for movement with the presser foot as it clamps a work piece of varying thickness to enter each spread loop of needle thread at a uniform distance from the presser foot, a needle thread take-up for giving up thread to the loop spreader and for setting each stitch in the work piece, and mechanisms for actuating the stitch-forming devices in proper timed relationships, in combination with locking thread controller means comprising an arm connected for actuation by the mechanism for actuating the needle guide to relieve the tension in the locking thread before each stitch is set in the work piece by the take-up.

32. A lock stitch sewing machine having a hook needle operating to enter and to withdraw a loop of thread from the work operated upon, other stitch-forming devices, means for measuring a predetermined length of thread for each stitch including a thread lock, and a thread supply from which the thread is withdrawn by the thread measuring means, in combination with means including a pull-off member located along the length of thread running from the thread lock to the supply and actuated in stopping the machine at the end of a seam for withdrawing thread from the supply sufficient in length to form the

32

first stitch in a new seam while said thread lock remains closed.

33. A lock stitch sewing machine having a hook needle operating to enter and to withdraw a loop of thread from the work operated upon, other stitch-forming devices, means for measuring a predetermined length of thread for each stitch including a thread lock, a thread supply from which the thread is withdrawn by the thread-measuring means, and driving and stopping mechanism for controlling the operation of the machine, in combination with means including a pull-off member located along the length of thread between the thread lock and the supply and connected to the driving and stopping mechanism for withdrawing thread when the machine is brought to rest by the driving and stopping mechanism and for releasing the withdrawn thread in a length sufficient to start a new seam when a new operation of the machine is started.

34. A loop lock stitch sewing machine comprising a work support, a curved hook needle operating to enter the work and to withdrawn to a fixed position with a loop of thread, means including an electrical resistance member mounted on the work support close to the work being operated upon and engageable by the needle thread at the end of the seam for severing the needle thread, means for gripping the free end of the needle thread remaining in the machine at the time that the needle thread is severed by the resistance member, means cooperating with the needle for spreading each loop of needle thread for entry of a loop of locking thread into the spread loop, take up means for applying a pull to the spread loop of needle thread, means for releasing the gripping means to allow the needle thread at the beginning of a seam to be drawn to a position in the work whereby the free end requires no trimming, and means separate from the loop spreader means for thereafter casting the loop from the hook of the needle during the initial portion of the motion of the needle toward the work from its fixed position.

35. A loop lock stitch shoe sewing machine comprising a work support, a curved hook needle operating to enter the work and to withdrawn to a fixed position with a loop of thread, means for spreading open the loop of withdrawn thread, means for carrying a loop of locking thread into the spread loop including a thread carrying finger through which the locking thread passes and a friction device movable with the finger and acting upon the locking thread ahead of its point of exit from the finger, means including an electrical resistance element mounted on the work support and engageable by the needle thread and a nipper jaw adapted to press the needle thread against the element for severing the needle thread at the end of the seam, means effective only at the completion of a seam for measuring a quantity of needle thread for the start of the next seam, means including a second electrical resistance element fixedly mounted above the work support and engageable by the locking thread for severing the locking thread at a predetermined distance from its point of exit from the thread finger, and means effective only at the completion of a seam for measuring a quantity of locking thread for the start of the next seam whereby, at the completion of each seam, the work is quickly removable from the machine with closely trimmed thread ends and without thread waste and, whereby further, measured quantities of needle and locking thread are available at the start of a new seam.
